J. W. HARSLEY AND M. P. APGAR.
SPRING COMPRESSOR.
APPLICATION FILED AUG. 5, 1921.
1,436,393. Patented Nov. 21, 1922.

UNITED STATES PATENT OFFICE.

JOHN W. HARSLEY AND MILTON P. APGAR, OF NEW YORK, N. Y.

SPRING COMPRESSOR.

Application filed August 5, 1921. Serial No. 489,977.

To all whom it may concern:

Be it known that we, JOHN W. HARSLEY and MILTON P. APGAR, citizens of the United States, residing at New York, borough of Manhattan, in the county of New York and State of New York, have invented certain new and useful Improvements in Spring Compressors, of which the following is a specification.

10 This invention relates to spring compressors or spring holding tools for use in connection with the assembling of poppet type valves in internal combustion motors. More particularly the invention relates to an improved combination spring compressor and spring clamp.

A primary object of this invention is to produce a device of simple and rugged construction which is efficient in compressing a stiff valve spring, and which may be used to conveniently insert the compressed spring into position upon the engine and in connection with the engine valve so as to avoid the danger to one's hands and awkward inconvenience heretofore experienced in placing valve springs on the motor.

It is an additional object to provide a spring compressor specially designed for heavy duty, which spring compressor may be bolted or screwed to a work bench in order that springs may be quickly and safely compressed, after which the spring is held in compressed position by a suitable clamp while the mechanic assembles or replaces the valve spring in the cylinder head or in position on an internal combustion motor.

The present invention relates to a spring compressor tool in a way similar to the spring compressor tool shown in our copending application for United States Letters Patent, the said application being filed July 2, 1920, Serial Number 393,479; excepting however the present application embodies certain improvements over our former application for patent, the said improvements more particularly relating to a bench type or heavy duty spring compressor for general shop work, whereas the compressor tool shown in the above identified application relates to a small portable compressor tool which is adapted to be carried in the tool box

of a motor car. The above identified application for patent has now resulted in a patent issued the sixth day of September, 1921, Patent Number 1,389,657.

The accompanying drawings show an embodiment of our invention, and though there is illustrated a preferred form of construction, we claim the right of protection as to such changes in design, construction and operation which obviously come within the scope of this invention.

Figure 1 shows a perspective view of the spring compressor with the compressing device or head raised high above a spring which is supported on a base.

Figure 2 is a rear view of the upper portion of the spring compressor showing the post and handle toggle mechanism.

Figure 3 illustrates a fragmentary part of the spring compressor, or a sectional view thereof as taken on the line 3—3 of Figure 2.

Figure 4 shows a perspective view of a spring which has been compressed by the compressor tool, and which spring is held in compressed position by the clamp illustrated in this view, thereby making the tool ready for insertion in position on an engine.

A spring compressor tool constructed in accordance with the principles of our invention, comprises a supporting post held by a base, and a guide bracket is adjustably mounted on the post. A compression rod is slidably confined in the guide bracket, and a lockable toggle-handle is arranged in connection with the compression rod to force this rod downwardly against a spring. The compression rod is provided with a head to engage and compress the spring, and this head together with the aforementioned base, is provided with a groove or grooves into which slides the jaws of a clamp. The spring clamp functions to clamp and hold the spring in any position to which it may be compressed. After the spring is thus compressed and clamped, the mechanic may remove the spring from the compressor and place the spring in the valve gear of an engine or any other place where the spring is to be used.

Referring now more in particular to the drawings for a detailed description of our

invention, there is shown a base or spring seat 6 having ears 7, and a hole is made through each ear to receive a bolt or screw to hold the base in anchored position on a work bench or table. The base is made with parallel grooves 8 which leaves a central ridge 9 in the base. A center pin 5 is anchored to the base 6 to receive and center the spring and the washer-seat to be compressed. This pin 5 is shown in Figure 1 projecting above the spring-washer-seat, and it is understood that this pin is a part fixed to the base 6 to help hold the spring in position while being compressed. A supporting post is mounted on the base and stands in a vertical position to hold the spring compressing parts. The upper end of the post is provided with a longitudinal slot 12 which is employed for the reception of a clamp screw, and the inner surface of the post is serrated or toothed as indicated by the numeral 14.

A guide bracket is adjustably supported on the upper end of the post 11 and this bracket comprises a pair of spaced parallel arms 16 which are integrally formed on a web 17. The web is serrated or toothed as indicated by the numeral 18, to correspond with the serrated surface 14 on the post. The guide bracket, or the web 17 thereof, is made with holes 19 to receive a clamp-screw 15 which is inserted through one of these holes and through the slot 12 to clamp the guide bracket in fixed position on the post. The outer end of each arm 16 is provided with a hole or guide bearing in which a compression rod is slidably held, as later described. A lug or journal support 20 is made a part of the guide bracket and extends outwardly therefrom to carry a toggle-handle, as later described.

A compression rod 22 is slidably mounted in the arms 16 and is held vertically over the base 6, and a head 23 is fixed to the lower end of the compression rod. The lower face of the head is grooved as indicated by the numeral 24.

A toggle-leverage is arranged to reciprocate the compression rod, and this leverage consists of a link 26 which is pivotally carried on the lug 20, and is likewise pivotally connected with a handle piece or link 27. A hole is made in this link 27 and a pin 28 pivotally joins the link 26 and the end of the handle link 27. A hand piece 29 is mounted on the outer end of the handle 27 and is so placed as to enable an operator to conveniently grasp the handle to operate the compressor. A stud-pin 30 is anchored to the link or handle 29 and is pivotally connected with the compression rod 22. The stud-pin 30 may be pivotally attached to the compression rod by a screw and nut connection 31 or any other appropriate means. The lug 20 and stud-pin 30 support

the toggle-leverage 26-27 in a position spaced from the post and guide bracket so that the toggle-leverage actuates freely of the post and other parts.

A spring clamp is constructed with a pair of movable jaws and has a clamp-screw to hold the jaws in fixed position. This spring clamp comprises two slide plates 33 movable one on the other. A clamp-screw 34 is passed through a slot 37 made in one plate and is anchored to the other plate so that when the screw 34 is tightened up the two plates 33 are held in fixed relation. A guide pin or bolt 36 is anchored to one of the guide plates and is slidably confined in a slot 37 made in the other plate. The guide pin has a large head, as shown in Figure 4, to effect a guiding action between the two slideable clamp plates. It is noted that the screw 34 and the guide pin 36 maintain the two clamp plates in alignment. The outer ends of the plates 33 are bent down to form jaws, and these jaws comprise parallel spaced fingers or jaw parts 32. One jaw of the clamp is supported in the grooves 8 of the base while the other jaw moves into the grooves 24 of the head.

It is understood by those conversant with the art, that springs, after being removed from the valves of an engine necessarily have to be compressed before they will easily and conveniently go back into position; and therefore this character of spring compressor finds a ready use in garages, work shops and assembling plants. A valve spring usually is provided with a seat-washer so that the spring will sit evenly on the engine push-rod. In the drawings the spring is designated by the numeral 39, and the washer 40 is shown with a receptacle-flange which provides a positive seating arrangement for the lower end of the spring. The washer 40 has a central hole through which the valve stem projects and this hole in the washer is placed over the center pin 5 of the base when a spring is to be compressed.

In compressing a spring and in the operation of this tool, the mechanic places the spring 39 and washer 40 on the center pin 5, and then moves the handle 29 downwardly causing the head 23 to engage the top end of the spring 39 and thus compress the spring downwardly until the spring coils of the spring are forced closer together which makes the spring appreciably shorter in length. The handle 29 is pushed downwardly until the links 26 and 27 are aligned, and the mechanic may push the handle 29 beyond the point of alignment so as to cause the links 26 and 27 to pass beyond the alignment centers of the several pivot points of the tool which effectively locks the head 23 downwardly against the compressed spring. The operator may then remove his hand and slip the clamp 33 into

the grooves 8 and 24, and thus the clamp is caused to engage the spring 39 and hold it in compressed position when the handle 29 is moved upwardly to remove the pressure of the head 23 from the spring. The clamp nut on the clamp screw 34 is necessarily tightly screwed up to lock the clamp plates 33 in immovable position prior to the release of the pressure on the spring.

10 The spring may now be safely removed from the spring compressor and inserted in working position on an engine.

It is to be noted that the grooves 8 and 24 are sufficiently deep to allow the jaws 32 of the spring clamp to easily slide into position over each end of the spring. It is understood that the spring is first compressed followed by the insertion of the clamp jaws 32 in the grooves 8 of the base 20 and grooves 24 of the head after which the clamp-screw 34 is tightened up, followed by raising the handle 29 and pressing head 23 to allow the spring to be removed from the base. The spring is now held by the 25 clamp, as shown in Figure 4, so that it may be safely and conveniently handled.

Having described our invention what we claim is:

1. A spring compressor tool comprising 30 a base, a post mounted on the base, a guide bracket adjustably carried by the post, a compression rod slidably confined in the guide bracket, and means for moving the compression rod under force to compress a 35 spring.

2. A spring compressor consisting of a base adapted to be anchored in fixed position, a supporting post rising from the base, a guide bracket, the contiguous faces 40 of the said supporting post and guide bracket being serrated to engage one the other, a clamping means to hold the guide bracket in fixed position on the post, a compression rod slidably confined in the guide bracket, 45 and means for forceably moving the compression rod downwardly toward the base to compress a spring.

3. A spring compressor consisting of a base, a post mounted on the base, a guide 50 bracket carried by the post, a compression rod slidably confined in the guide bracket, and a toggle handle arranged to work the compression rod downwardly toward the base to compress a spring, and said base and compression rod having grooves for the reception 55 of a spring clamp.

4. A spring compressing tool consisting 60 of a base acting as a seat to hold a spring to be compressed, a post rising from the seat, a spring compressing device, mounted on the post, and said compressing device being adjustably secured to the post for the purpose of accommodating springs of various lengths.

65 5. A spring compressing tool consisting

of a base acting as a seat to support a spring to be compressed, a bracket carried by the post, a slidable compressing device carried by the bracket, a toggle carried by the bracket, and a handle establishing a connection between the toggle and the slid- 70 able compressing device to forceably operate the compressing device and lock it against a spring under compression.

6. A spring compressor comprising a base 75 to support a spring to be compressed, a post carried on the base, a guide bracket adjustably clamped on the post, a clamping-screw related with the post and guide bracket to adjustably hold the bracket at any de- 80 sired position on the post, and a compressing device slidably carried on the guide bracket.

7. A spring compressor as defined in claim 9 wherein the post and the guide bracket is provided with a slot and a number of holes 85 for the purpose of receiving the clamp-screw in order that the said clamp-screw may be interchanged to any of the afore-said holes and passed through the afore-said slot to adjust the guide bracket rela- 90 tively to the post.

8. A spring compressor comprising a seat to hold a spring, said seat having grooves made therein under the supported end of the spring, a post mounted on the seat, a 95 compression rod carried by the post, a head secured to the compression rod, said head having grooves therein adjacent to the upper end of the spring to be compressed, and means for moving the compression rod and 100 head against the spring.

9. A spring compressor comprising a seat to hold a spring, said seat having grooves made therein under the supported end of the spring, a post mounted on the seat, a compression rod carried by the post, a head secured to the compression rod, said head having grooves therein adjacent to the upper end of the spring to be compressed, means for moving the compression rod and 105 head against the spring, and a clamping device slidable through the aforesaid grooves made in the seat and the head to confine the spring in compressed position.

10. A spring compressor consisting of a 110 base provided with a groove, a spring to be compressed set on the base over the groove, a post mounted on the base, a compressing device carried by the post and positioned in line with the spring, a grooved 115 head carried by the compressing device and adapted to move against the end of the spring, a toggle to actuate the compressing device, and a spring clamp slidable into the grooved head and grooved base at each 120 end of the spring to hold the spring under compression.

11. A combination spring compressor and spring clamping tool, consisting of a 125 grooved base upon which a spring is sup- 130

ported, a compression rod, a grooved head carried by the compression rod and adapted to be forced against the spring, a toggle to actuate the compression rod, a spring clamp, 5 jaws formed on the spring clamp and slideable into the grooved head and base at each end of the compressed spring and a clamp-screw related with the spring clamp to hold

the clamp in fixed position against the compressed spring.

In testimony whereof, we have hereunto affixed our hands this 29th day of July, 1921, 10 in the city and county of New York, borough of Manhattan, and State of New York.

JOHN W. HARSLEY.
MILTON P. APGAR.
